UNITED STATES PATENT OFFICE.

JOSEPH KEENE, OF CHICAGO, ILLINOIS.

SPRING-HINGE.

SPECIFICATION forming part of Letters Patent No. 609,585, dated August 23, 1898.

Application filed April 18, 1898. Serial No. 677,994. (No model.)

To all whom it may concern:

Be it known that I, JOSEPH KEENE, a resident of the city of Chicago, in the county of Cook and State of Illinois, have invented certain new and useful Improvements in Hinges, of which I do declare the following to be a full, clear, and exact description.

The present invention has relation more particularly to that class of hinges known as "spring-hinges;" and the object of the invention is to provide an improved construction of hinge-leaf, whereby one end of a spring is connected to the hinge.

The invention will be hereinafter described with reference to the accompanying drawings and particularly defined at the end of the specification.

Figure 1 is a front view of a spring-hinge embodying my invention, the door to which the hinge is attached being shown as open and brought to a point parallel with the door-jamb. Fig. 2 is a view in elevation of a partially-shaped plate-metal blank from which my improved hinge-leaf will be formed. Fig. 3 is a lower end view of the blank shown in Fig. 2. Fig. 4 is a view in elevation of the finished hinge-leaf shown in Fig. 2. Fig. 5 is a bottom plan view of the leaf shown in Fig. 4. Fig. 6 is a view in vertical section through the eye at one side of the body of the hinge-leaf, a portion of the leaf being shown in elevation. Fig. 7 is a view in cross-section on line 7 of Fig. 4.

In Fig. 1 of the drawings I have shown my invention as embodied in a double-acting spring-hinge of the type set forth in United States Letters Patent No. 227,786, granted to Daniel W. Housley May 18, 1880, this being the type of hinge to which my invention is more especially applicable, although it will be understood that the invention is not restricted to this precise form of hinge, since it is susceptible in hinges of other construction.

A and B designate, respectively, the door and door-jamb to which the plates or castings C of the hinge will be attached. At the upper and lower ends each of the plates or castings C has connected thereto a pintle-support D, united by a suitable pintle E with the adjacent intermediate or central leaves F and G. The upper intermediate leaf F is

provided at its lower end with an eye adapted to receive the shank of the spindle H, that is connected to the upper end of the coil-spring J in the usual manner, while the lower intermediate leaf G is provided at its upper edge with a stud or projection g, adapted to enter and hold the lower end of the coil-spring. It will be understood, of course, that behind the intermediate leaves F and G (shown in Fig. 1) there will be suitable pintle-supports D; but the location of these supports is the same as in ordinary double-acting hinges, and as they form no part of this invention it has not been deemed necessary to illustrate them in the drawings.

The present invention relates particularly to the construction of the intermediate leaf F, and more especially to the means whereby this leaf is adapted for connection with the spindle H, to which the upper end of the coil-spring J is attached. The hinge-leaf F is formed from a blank of sheet-steel, the edges of which are preferably cut, so that when bent they shall form the pintle-sockets 2 and 3 at the sides of the leaf. In order to form the eye at the base of the upper intermediate leaf, I first cut the blank with an extension f, in which is formed an eye f', and in the edges of this extension f are preferably formed the notches f''. The extension f is connected with the body of the leaf F by a contracted neck f³, and the neck of the extension is of sufficient length to permit it to be doubled or folded upon itself, as clearly shown in Figs. 2 to 6 of the drawings. At the sides of the base of the neck f³, whereby the extension f is connected with the body of the leaf, are formed the slits f⁴ to form a recess adapted to receive the extension f and guard the same against lateral strain. Preferably, also, the lower edge of the leaf F is provided with lugs f⁶, that depend from the lower edge of the leaf at each side of the neck f³, and these extensions are adapted to enter the notches f² in the edges of the extension f when the extension is doubled upon itself, and the lower ends of the lugs f⁶ are then forced inward, as shown in Figs. 4 and 6 of the drawings, so as to overlap the lower face of the extension f and firmly brace and retain the same against all strains incident to the action of the spring.

In the lower portion of the leaf F and above

the extension f is formed an aperture f^7 , that is adapted to register with the aperture f' after the shank or neck of the extension f has been doubled upon itself, the purpose of this 5 aperture f^7 and of the aperture f' being to receive the upper portion of the spring-spindle H, as clearly seen in Fig. 1 of the drawings.

After the blank from which the leaf F is to be formed has been cut it will by means of 10 suitable dies be brought by successive operations to the shape shown in Figs. 2 and 3 of the drawings, after which the extension f will be forced toward the body of the leaf, thereby doubling the shank or neck f^8 upon itself and 15 causing the extension f to enter the recess of the body formed by the removal of a portion of the shank formerly between the slit at the lower edge of the leaf. At such time the lugs f^6 will pass through the notches f^2 , and the 20 ends of the lugs will be upset, so as to lap over the outer face of the extension f , as seen in Figs. 4 and 6, and thus securely retain the extension f against possible distortion incident to the action of the spring J. When the 25 extension f has been thus brought to the position seen in Figs. 4, 5, and 6 of the drawings, the aperture f' will register with the aperture f^7 , so that the spindle H can be inserted through the aperture f' and into the aperture f^7 . The spindle H will be provided 30 with the usual holes h , adapted to receive a pin h' , whereby the spring will be retained in any position to which it may be adjusted. In order to more securely retain the pin h' in 35 place, I form the edges of the aperture f^7 on the front and back side of the hinge-leaf F with notches or depressions f^9 , into which the ends of the pin h' will pass.

By forming the hinge-leaf F with an extension f integral therewith and by forcing this extension into a recess formed in the body of the leaf by the removal of a portion of the shank between the slit f^4 of the body the extension f will be securely braced. So, 40 45 also, by forming notches f^2 in the extension f , as I prefer to do, a still more effective guarding of the extension, particularly against tor-

50 sional strains, is afforded. So, also, the provision of lugs f^6 , that extend beyond and are upset against the extension f , still more effectively serve to retain the extension in place and give rigidity thereto.

It is manifest that my invention may be practiced without the employment of all of the details above set forth, and I do not therefore wish the invention to be understood as restricted to such details except as the same are specifically defined in the following claims.

Having thus described my invention, what 60 I claim as new, and desire to secure by Letters Patent, is—

1. A leaf for a spring-hinge consisting of a plate of sheet metal one edge of which has formed integral therewith a perforated extension, said extension being bent at an angle 65 to the body of the hinge-leaf and folded upon itself and into a recess in the body of the leaf, the body of the hinge-leaf being provided with an aperture above said extension. 70

2. A leaf for a spring-hinge consisting of a plate of sheet metal one edge of which has formed integral therewith a perforated extension, said extension being bent at an angle 75 to the body of the hinge-leaf and folded upon itself and into a recess at the edge of the leaf, said extension being provided with notches to receive adjacent parts of the leaf-body, the body of the leaf being provided with an aperture above said extension. 80

3. A leaf for a spring-hinge consisting of a plate of sheet metal one edge of which has formed integral therewith a perforated extension, said extension being bent at an angle 85 to the body of the hinge-leaf and folded upon itself, the body of the hinge-leaf being provided at the base of said extension with lugs between which said extension rests, said lugs engaging said extension to hold the same in place.

JOSEPH KEENE.
